CLAIM

The ornamental design for a downstrut for the swing arm of a suspension bicycle, as shown and described.

DESCRIPTION

FIG. 1 is a side elevational view of a downstrut for the swing arm of a suspension bicycle,

FIG. 2 is a front elevational view of the downstrut for the swing arm of a suspension bicycle,

FIG. 3 is a top view of a downstrut for the swing arm of a suspension bicycle,

FIG. 4 is a bottom view of the downstrut for the swing arm of a suspension bicycle; and,

FIG. 5 is a perspective view from the rear showing the downstrut for the swing arm of a suspension bicycle.

The broken lines shown in all drawing views are for illustrative purposes only and form no part of the claimed design.
